(57) **CLAIM**

The ornamental design for canisters for a roll off film system, as shown and described.

DESCRIPTION

FIG. 1 is a front perspective view of canisters for a roll off film system showing our new design;

FIG. 2 is a rear perspective view thereof;

FIG. 3 is a rear side elevational view thereof;

FIG. 4 is a front side elevational view thereof;

FIG. 5 is a top plan view thereof;

FIG. 6 is a bottom plan view thereof;

FIG. 7 is a right side elevational view thereof; and

FIG. 8 is a left side elevational view thereof;

FIG. 9 is a front perspective view of the canisters for a roll off film system attached to a goggle assembly; and,

FIG. 10 is a rear perspective view thereof.

The broken lines in the drawings illustrate environmental features and form no part of the claimed design.
